HARRY D. JOHNSON, OF CHICAGO, ILLINOIS, ASSIGNOR OF ONE-THIRD TO RALPH D. KRAETSCH AND ONE-THIRD TO HARRY SVARRER, BOTH OF CHICAGO, ILLINOIS

AUTOMOBILE ENGINE COOLING SYSTEM

Application filed September 16, 1931. Serial No. 563,117.

My invention relates to an improvement in automobile engine cooling systems and has for one object the provision of improved means for maintaining circulation of a cooling fluid, such as water, about a machine, engine or the like. I illustrate my invention in connection with the radiator and engine block of an ordinary automobile, but it will be realized that it may have other application.

One object is the provision of means for circulating cooling water through the engine block of an automobile without the employment of pumps or positively and mechanically actuated conveying means. Other objects will appear from time to time in the course of the specification and claims.

I illustrate my invention more or less diagrammatically in the accompanying drawing, 20 wherein

Figure 1 is a side elevation with parts in section;

Figure 2 is a front elevation;

Figure 3 is a section on the line 3-3 of Figure 2;

Figure 4 is a diagrammatic view with parts in section; and

Figure 5 is a view similar to Figure 4, of a variant form.

Like parts are indicated by like symbols throughout the specification and drawing.

Referring to the drawing, A generally indicates any suitable engine having the water jacket structure A¹ about the cylinders. A² indicates the intake manifold and A³ generally indicates the carburetor structure.

B generally indicates the radiator structure of the automobile having a passage B¹ extending from a lower portion of the radiator to the engine block for communication with the water jacket A¹. B² is a return water passage from the water jacket which may discharge as at B³ within the radiator structure.

Within the radiator structure is a passage member generally indicated as C which is closed at the top as at C¹ but open at the bottom as at C², at a point well below the normal level of water within the radiator. C³ indicates the cooling liquid, water or the like.

D indicates a pipe line extending from the

intake manifold A² to an upper portion of the passage C. It is essential that the outlet connection between the passage C and the passage D be above the level of the water within the passage C. Hence it is illustrated in Figure 1 as connecting with the passage C at a point above the water inlet B². The open bottom C² of the passage C may be intermittently closed as by the valve member E, which may be a plate or disc normally upwardly drawn as by the spring E¹. It may be guided for example by the stem E² passing through the guide or guides E³. It will be understood that pressure within the chamber C, for example the pressure of a column of water, will move the closure E downwardly and permit the water to seek its general level in the radiator. On the other hand, any back or upward pressure closes the closure E, preventing the flow of water inwardly and upwardly into the container C from the general interior of the radiator.

G indicates an outlet or overflow passage for the radiator, positioned exteriorly of the passage C. G¹ indicates any suitable means, for example the outlet with the valve G², for draining the radiator.

Figure 4 illustrates diagrammatically the function of the device. Figure 5, with a slightly variant structure, is also a diagrammatic illustration of the function of the device.

It will be realized that whereas I have described and shown a practical and operative device, nevertheless many changes might be made in the size, shape, number and disposition of parts without departing from the spirit of my invention. I therefore wish my description and drawing to be taken as in a broad sense illustrative and diagrammatic rather than as limiting me to my specific showing.

The use and operation of my invention are as follows:

It will be clear from the structure herein shown that when the engine is in operation the inflow of fuel and air through the intake manifold will cause suction, through the pipe line D, in the container C. This creates or tends to create a vacuum in the interior of the

container or passage C. The surface of the water within the container or passage C is sufficiently large so that the vacuum will not be effective substantially to raise the level of the water within the chamber C. On the other hand, it will be sufficient to cause a flow of water through the passage B² and into the passage C. In order further to resist the tendency of the water to rise in the passage C 5 I may provide the closure means E above described. In any case, the suction through the passage B² will withdraw water from the water jacket A¹ as diagrammatically illustrated in Figures 4 and 5, and this will tend to raise the level of water in the passage C above the normal level of water in the radiator itself. The weight of the column of water so accumulated will force open the closure E and the water will flow downwardly 10 through the bottom of the member C to join with the water in the radiator. Thus, a circulation is maintained from the radiator through the passage B¹ to the engine block A¹, and from the engine block A¹ through the passage B² to the chamber or passage C and thence through the closure E to the interior 15 of the radiator.

Considering Figure 4 for example, it will be clear that while there may be atmospheric pressure or approximate atmospheric pressure above the water in the radiator outside of the passage or container C, there will be suction or a relative vacuum in the space above the water level within the passage C. This relative suction will not result in any rise in level of the water from the bottom of the passage C, whether because of the area of water exposed or because of the use of the closure E. It will cause withdrawal of water through the passages B¹ and B² from the radiator to the interior of the passage C, thus causing the necessary circulation of the cooling medium.

Referring to Figures 4 and 5 it will be noted that no closure E is employed and in many circumstances it may be possible to dispense with its use. What is essential is that the level of water when the device is running shall not rise above the inlet of the member B² and the parts are illustrated in all figures disposed in such fashion as to prevent any such rise of level.

I claim:

1. In a device for maintaining the circulation of a cooling liquid for an engine, an engine, a water jacket associated therewith, a radiator, a chamber within said radiator having a bottom opening located below the normal water level in said radiator, an outlet passage member extending from the radiator, below the water line, to the water jacket, an inlet passage member extending from the water jacket to the interior of said chamber at a level above the water line, and a suction passage in communication with said cham-

ber, above the level of said outlet passage, and means for maintaining a suction therethrough.

2. In a device for maintaining the circulation of water for an engine, an engine, an inlet manifold therefor, a water jacket for the engine, a radiator, a chamber within the radiator having a bottom opening located below the normal water level in said radiator, an outlet passage member extending from the radiator, below the water line, to the water jacket, an inlet passage member extending from the water jacket to the interior of said chamber at a level above the water line, and a suction passage extending from the inlet manifold to said chamber at a level above the level of said outlet passage.

3. In a device for maintaining the circulation of a cooling liquid for an engine, an engine, a water jacket associated therewith, a radiator, a chamber in communication with said radiator at a point below the normal water level in said radiator, an outlet passage member extending from the radiator, below the water line, to the water jacket, an inlet passage member extending from the water jacket to the interior of said chamber at a level above the water line in said chamber, and a suction passage in communication with said chamber, above the level of said outlet passage, and means for maintaining a suction therethrough.

4. In a device for maintaining the circulation of a cooling liquid for an engine, an engine, a water jacket associated therewith, a radiator, a chamber in communication with said radiator at a point below the normal water level in said radiator, an outlet passage member extending from the radiator, below the water line, to the water jacket, an inlet passage member extending from the water jacket to the interior of said chamber at a level above the water line in said chamber, and a suction passage in communication with said chamber, above the level of said outlet passage, said suction passage extending to the inlet manifold of said engine.

Signed at Chicago county of Cook and State of Illinois, this 9th day of September 1931.

HARRY D. JOHNSON.
